Fig. 5

FIG. 1 is a top view of the automobile embodying my new design;

FIG. 2 is a side elevation of the automobile shown in FIG. 1;

FIG. 3 is a view of the front end of the automobile shown in FIGS. 1 and 2;

FIG. 4 is a view of the rear end of the automobile shown in FIGS. 1 and 2;

FIG. 5 is a section in elevation taken at lines 5—5 of FIG. 2;

FIG. 6 is a section in elevation taken at lines 6—6 of FIG. 2.

The dominant features of my design reside in the portion shown in full lines.

I claim:

The ornamental design for an automobile, substantially as shown and described.
